UNITED STATES PATENT OFFICE.

HYYM E. BUC, OF ROSELLE, NEW JERSEY, ASSIGNOR TO STANDARD OIL DEVELOPMENT COMPANY, A CORPORATION OF DELAWARE.

PURIFYING ALCOHOLS.

No Drawing.

Application filed July 31, 1923. Serial No. 854,931.

This invention relates to the art of purifying water-soluble alcohols and will be fully understood from the following description.

5 When alcohols are first produced, particularly by the process in which an unsaturated hydrocarbon, such as ethylene, propylene, and the like, is combined with sulfuric acid and the product hydrolyzed by 10 means of water, they usually carry persistent odors foreign to the alcohol proper. The nature of the impurities varies and is not always known. In the case of secondary and tertiary alcohols produced from unsaturated compounds there are present besides olefines, ethers and higher alcohols, also sulfur compounds of unknown structure. Various chemical treatments for purification have been devised but such treatments are often apt to introduce other impurities by reaction with the alcohols or 20 with the constituents carried by the alcohols.

In accordance with the present invention, I provide a purifying treatment which being 25 of a physical nature makes possible the production of high grade alcohols, particularly from the point of view of odor, without damage to the alcohol molecules themselves. In most cases this treatment alone is sufficient 30 but if desired a light chemical treatment may precede or follow.

I treat the alcohol as such, or after diluting with water as desired, with an organic liquid capable of taking up the undesired 35 constituents. As such liquid, various substances may be used, keeping in general the properties also of ready separability from the alcohol, and such a degree of purity as will avoid any side contamination. Various 40 hydrocarbons in particular are serviceable, and the petroleum hydrocarbons especially are cheap and widely available, and by preference I employ highly refined white (colorless) petroleum oils, more especially products of high boiling point, for example of 45 initial boiling point above 500° F.

The treating liquid is thoroughly mixed and agitated with the alcohol to be treated, and the mixture is then allowed to settle for 50 stratification into layers and the treating liquid is drawn off. Desirably this treatment is repeated with another charge of treating liquid; and by a plurality of such treatments in succession, the desired degree of 55 purification may be effected. The alcohol is

then submitted to distillation or any other finishing treatment desired.

The treating liquid may be further used to treat fresh alcohol until its capability of taking out the impurities has reached a 60 practical limit.

As an example illustrative of my process: Crude isopropyl alcohol preferably diluted with about a volume of water, and a colorless odorless petroleum oil of about 570- 65 580° F., initial boiling point and having a viscosity of around 205-215 Saybolt at 100° F., are mixed in an agitator device and are then settled to allow stratification into layers. The oil is removed and the alcohol is again 70 agitated with another portion of oil. From six to eight such washings are generally sufficient. The alcohol is then rectified.

The relative amount of oil employed may vary within wide limits, but by using continuous agitators and suitable separators relatively small amounts are sufficient, and by introducing the fresh oil toward the end and cycling back used oil for the earlier treats, high efficiency may be realized. The oil 80 which is fully loaded up may be subjected to steam distillation or refining treatments known in the petroleum industry and is then again fully available.

While I have referred more particularly to 85 a highly refined white oil of petroleum character, it is to be understood that I contemplate using also various less highly refined petroleum oils, particularly those of the lubricating range, and even oils of still lower 90 boiling points, keeping in view of course the desirability in any case of a sufficiently practicable separability between the alcohol to be treated and the hydrocarbons used to enable a ready separation. And while I have 95 referred more especially to isopropyl alcohol by reason of its predominant importance, it will be understood that other water-soluble alcohols can likewise be treated.

What I claim is:

1. In a process of purifying an alcohol derived from unsaturated hydrocarbons and capable of removal by stratification from admixture with petroleum oil, the improvement which comprises agitating the alcohol 105 with a highly refined petroleum oil having an initial boiling point of about 570 to 580° F., separating the oil, repeating the treatment with other charges of a like oil a plurality of times, and distilling the alcohol. 110

2. In a process of purifying an alcohol derived from unsaturated hydrocarbons and capable of removal by stratification from admixture with petroleum oil, the improvement 5 which comprises agitating the alcohol with a colorless petroleum oil having a boiling point above 500° F., separating the oil, repeating the treatment with other charges of a like oil a plurality of times, and dis- 10 tilling the alcohol.
3. In a process of purifying an alcohol derived from unsaturated hydrocarbons and capable of removal by stratification from admixture with petroleum oil, the improve- 15 ment which comprises mixing the alcohol with a heavy petroleum oil, allowing the mixture to stratify, whereby two layers are

formed containing respectively the bulk of the alcohol and the bulk of the oil, and separating the layers. 20

4. Method according to claim 3, in which a colorless petroleum oil having an initial boiling point of about 500° F. is used as the purifying agent.

5. In a process of purifying an alcohol derived from unsaturated hydrocarbons and capable of removal by stratification from admixture with petroleum oil, the improvement which comprises treating the alcohol with refined petroleum hydrocarbons of boiling point above 500° F. and separating the hydrocarbons. 25 30
